The ornamental design for an insulator cup for the support of neon lights, as shown and described.

DESCRIPTION

FIG. 1 is a top, side perspective view of an insulator cup for the support of neon lights showing my new design;
FIG. 2 is an opposite side elevational view thereof;
FIG. 3 is a bottom plan view thereof;
FIG. 4 is a cross-sectional view thereof, taken on line
4—4 of FIG. 3;
FIG. 5 is a top plan view thereof; and,
FIG. 6 is a front elevational view thereof.

FIG. 1

FIG. 2

FIG. 3

FIG. 5

FIG. 4

FIG. 6
